SIGN AND DISPLAY DEVICE

Filed Oct. 2, 1928

UNITED STATES PATENT OFFICE

MAX WASSERBERG, OF FLUSHING, NEW YORK, ASSIGNOR OF ONE-HALF TO SAMUEL STEINFELD, OF NEW YORK, N. Y.

SIGN AND DISPLAY DEVICE

Application filed October 2, 1928. Serial No. 309,834.

This invention relates to signs or display devices of any kind or class and particularly to devices utilizing daylight as a source of illumination; and the object of the invention is to provide a device of the class specified employing a translucent body or panel arranged in one wall of the device, preferably the upper wall thereof, with means for supporting a characterized display element in juxtaposition to said panel permitting light rays to pass through said display element onto a reflector surface, upon which the characters of said element may be seen from an opening provided in one wall of the device angularly disposed with reference to said reflecting surface; a further object being to provide means for movably and detachably supporting the display element with relation to said panel; a further object being to provide means for continuously moving a display element with reference to said panel to produce on the reflector surface a moving characterized display; a further object being to provide means for adjusting the angular positioning of the device with reference to a standard or support; a still further object being to provide means for utilizing artificial light for transmission through the panel; and with these and other objects in view, the invention consists in a device or apparatus of the class specified, which is simple in construction, efficient in use, and which is constructed as hereinafter described and claimed.

The invention is fully disclosed in the following specification, of which the accompanying drawings form a part, in which the separate parts of my improvement are designated by suitable reference characters in each of the views, and in which:—

Fig. 1 is a longitudinal, sectional view through one form of device made according to my invention and illustrating one method of its operation.

Fig. 2 is a front and sectional view of the structure shown in Fig. 1.

Fig. 3 is a plan view of another form of device which I employ.

Fig. 4 is a section on the line 4—4 of Fig. 3 with part of the construction broken away.

Fig. 5 is a perspective view of a device similar to that shown in Figs. 3 and 4 and showing a modification; and,

Fig. 6 is a perspective view showing another modified form of construction.

For the purpose of illustrating one method of carrying my invention into effect, I have shown in Figs. 1 and 2 of the drawings, a casing 10 which is substantially rectangular in form, the front wall being provided with a rectangular opening 11, and the top wall with an opening 12. The back of the casing 10 is preferably open and adapted to be closed by a cover 13 which in the construction shown carries a supplemental bottom 14 upon which a small electric motor 15 is supported as well as other parts of the device later described.

Arranged in the opening 12 is a panel 16, which in most uses of the device will be composed of translucent material but may in some uses, consist of transparent material, the materials employed in either use, being glass, paper, celluloid or any other similar material.

The panel 16 is held in place by a frame member 17, movable keepers 18 permitting the attachment and detachment of said panel. Arranged within the casing 10 and at an angular position with reference to the front and top walls thereof adjacent the openings 11 and 12 is a reflector 19 which may constitute a mirror or a metallic or other reflector surface of any kind or class, a mirror being preferably employed.

This reflector is supported in connection with the casing 10 by a frame 20 which includes side wall members 21. The arrangement of the reflector 19 is such that light passing down through the panel 16 will be reflected outwardly through the opening 11 in the front wall of the casing. Supported in the path of light preferably adjacent the panel 16 is a display element 22, preferably in the form of a moving body, which in the construction shown is annular and in the form of a stenciled annular strip of metal, paper or other material, the characteristics of the element 22 being stamped therefrom, permitting the passage of light through the cut out

portions only, the remainder of said element being opaque, and any word or series of words may be arranged circumferentially of the element 22 to be transmitted onto the reflector 19 in the rotation of the element 22.

In the construction shown, the element 22 is supported upon a mounting ring 23 which in turn is detachably coupled with a semi-circular member 24 driven by the motor 15 through reduction gearing comprising a small pinion 25 on the motor shaft and a comparatively large gear 26 on the shaft 27 of the member 24, said shaft having a suitable bearing 28 arranged in a support 29 secured to the bottom 14.

The ring 23 is preferably made detachable with respect to the member 24 to facilitate the placement of different elements 22 thereon, and this detachable connection may be made in any desired manner, for example by providing a channel 23a at one side of the frame 23, in which the peripheral edge of the member 24 seats.

Wires 30 and 31 from a suitable source of electric supply are coupled with the motor 15 through a switch device 32 supported in connection with the cover 13 whereby the stopping and starting of the device may be controlled. It will be understood at this time that the switch 32, motor 15, member 24 and frame 23 may be removed from the casing 10 as a unit for repair, cleaning or other purposes and for the purpose of replacement of characterized display elements 22 in the several uses of the device.

With the construction shown in Figs. 1 and 2, it will be understood that the element 22 may be characterized in any desired manner and may constitute an advertising display, a pictorial or other educational or amusement display or in fact, a characterized element of any kind or class regardless of the particular structure of the element. This element may, as hereinbefore stated, be opaque, with the characteristics stamped therefrom or may be translucent or transparent with the characteristics printed or otherwise applied thereto, and in fact picture films may be employed.

In the several uses of elements 22, it will be understood that any suitable means of movement or actuation of the element may be employed as well as different types of motive power, the structure shown in the accompanying drawing being merely for the purpose of illustrating one use of my invention or method of carrying it into effect. By virtue of the detachable mounting of the panel 16, it will be understood that panels of different kinds or characteristics may be employed in the several uses of the device and especially in changing the color of such panels, it being understood that one color may be used throughout the entire panel or a combination of colors may be incorporated therein.

In addition to the movable characterized element as disclosed in Figs. 1 and 2 of the drawings, my invention further consists in providing a device wherein the movable feature is removed, and means is provided for detachably supporting a characterized element adjacent the panel of the device. This form of construction is very useful in various types of advertising displays, and especially wherein it is desirable to change the characterized element from time to time.

In carrying this type of a device into effect, I employ as seen in Figs. 3 to 6 inclusive, an oblong rectangular casing 33, the front wall of which is provided with an opening 34, the top wall with an opening 35 closed by a panel 36 similar in all respects to the panel 16 and held in place by a frame 37 and keepers 38.

Supported in the casing 10 in a position angular with reference to the top and bottom walls thereof is a reflector 39 composed of glass, metal or other material presenting a reflector surface. Arranged within the casing adjacent the top and side walls thereof are guide channels 40 in which is slidably mounted a frame 41 adapted to support a characterized element 42. This frame is of channel form in cross section at the front and sides thereof, the back being open as seen at 43, Fig. 4, to permit the insertion of the element 42. The rear end of the frame is provided centrally with an upwardly directed finger piece 44, by means of which said frame may be manipulated. The back wall 33a of the casing is removable to permit the insertion of the reflector 39 which in the construction shown is supported in guide channels 45 on the inner faces of the side walls of the casing.

In the construction shown in Figs. 3 to 5 inclusive, I preferably provide a support for the casing 33 in the form of a standard 46 having a large base portion 47 and a split semi-circular socket 48 at the upper end of the standard and adapted to receive a ball end 49 on a member 50 secured to the bottom wall of the casing. A winged nut and screw construction 48a is employed on the socket 48 to regulate the tensional or frictional engagement of said ball end 49, permitting the adjustment of the casing universally upon the support or upper end of the standard 46. This type of display may be conveniently used on counters, in window displays and the like to exhibit advertising or other characterized matter relating to goods placed on display and may include for example, sales or price cards.

For night display, I may support upon the top wall of the casing 33, a hood 51 in connection with which is supported an incandescent light 52, the socket of which opens outwardly through the back of the hood 51, said hood tapering to the side walls of the

casing as clearly seen in Fig. 5. The hood 51 may be removed when the device is used in daylight, it being understood that where overhead lights are employed, for example, 5 in window displays, the hood 51 is not essential.

In Fig. 6 of the drawings, I have shown a modified method of supporting the casing 33 and in this construction the support involving the parts 46-50 inclusive are eliminated, and in this construction, the rear wall of the casing is provided adjacent the sides thereof with strap retaining members 53 in connection with which straps 54 are mounted 15 for strapping the casing upon a bar, rod or other support.

It will be understood that my improved device may be mounted in connection with supports of any kind or class and suitable means 20 will be provided to retain the device in connection with said support. In like manner, the shape or form of the casing may be varied, and while I have referred to certain specific uses of the device and have illustrated certain 25 details of construction for carrying my invention into effect, it will be understood that I am not necessarily limited to these uses nor to the structures herein disclosed, and various changes therein and modifications thereof 30 may be made within the scope of the appended claims without departing from the spirit of my invention or sacrificing its advantages.

Having fully described my invention, what 35 I claim as new and desire to secure by Letters Patent, is:—

1. A device of the class described comprising a casing, an opening in one wall of said casing, a reflector angularly disposed with 40 reference to the line of vision through the opening in said casing, means admitting rays of light from a source into the casing and onto said reflector in a path angular with respect to said line of vision, a translucent panel 45 constituting part of said last named means, means for supporting a characterized element having translucent properties adjacent said panel in said path of light, said last named means being detachable with respect 50 to the casing, and means for moving said element to bring successive sections thereof into position relatively to said panel and reflector, said last named means involving a source of power arranged in said casing and in operative 55 engagement with the element supporting means through a member movable around said angularly disposed reflector.

2. A device of the class described comprising a casing, an opening in one wall of said 60 casing, a reflector angularly disposed with reference to the line of vision through the opening in said casing, means admitting light into the casing and onto said reflector in a path angular with respect to said line of vision, a translucent panel constituting part of 65

said last named means, means for supporting a characterized element having translucent properties adjacent said panel in said path of light, said last named means being detachable with respect to the casing, means for 70 moving said element relatively to said panel, said last named means involving an electric motor arranged in said casing and a switch controlling the current supply to said motor and a frame on which said motor, switch and 75 element supporting means is mounted to constitute a unit removably supported in connection with said casing.

In testimony that I claim the foregoing as my invention I have signed my name this 28th day of September, 1928.

MAX WASSERBERG.
